UNITED STATES PATENT OFFICE.

ALBERT E. MAYNARD, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

GRINDING TOOL.

1,405,424.

Specification of Letters Patent.

Patented Feb. 7, 1922.

Application filed May 20, 1920. Serial No. 382,801.

To all whom it may concern:

Be it known that I ALBERT E. MAYNARD, a citizen of the United States, residing at Southbridge, in the county of Worcester and 5 State of Massachusetts, have invented certain new and useful Improvements in Grinding Tools, of which the following is a specification.

This invention relates to improvements in 10 lens grinding machinery and has particular reference to machines employed in the production of cylindrical or toric lenses.

Prior to my invention difficulty has been experienced in connection with machines of 15 this character due to the necessity of absolutely accurate blocking of the lens so that it might come in the necessary relationship to the grinding tool, this being particularly the case when a cylinder correction possessing 20 definite axis was to be ground. Difficulty also has been experienced in those cases where due to an imperfection of the machine improper operation or the like the grinding of the lens after it was started was found to 25 be off the desired axis position and it was desired to slightly vary the relationship.

One of the purposes of my present invention, therefore, is to make it possible to adjust the relative axial position of the lens 30 and tool at any point during the grinding operation and to make it unnecessary to block the lens with particular exactitude or to compensate for any inaccuracies of the blocking or grinding.

35 A further object of my present invention is the provision of a novel and improved mechanism which shall not only accomplish this purpose, but which shall in addition be so constructed that various forms of grinding tools may be interchangeably employed 40 in connection with a single grinding machine, thus making the machine universally adaptable and not requiring the purchase of special tools for use in connection with the 45 machine.

Other objects and advantages of my improved construction should be readily apparent by reference to the following specification taken in connection with the accompanying drawings, and it will be understood 50 that I may make any modifications in the specific details of construction shown and described within the scope of the appended

claims without departing from or exceeding 55 the spirit of my invention.

Figure I represents a side elevation of one embodiment of my improvements.

Figure II represents a vertical section therethrough.

Figure III represents a vertical section at right angles to Figure II, illustrating another form of tool in position in the device.

Figure IV represents a plan view of the toric adapter.

In the drawings, the numeral 1 designates the conical base portion of my improved lens grinding tool, having an interior socket 2 of suitable form to fit on a grinding machine spindle. The upper portion of the base is 70 centrally hollowed to form the socket 5 surrounded by a collar 6 preferably provided with suitable lag or set screw 7.

In that form of invention illustrated in Figures I and II, I have shown as fitting 75 within the socket 5 the shank 8 of the stud 9 for the lens grinding tool 10, this shank 8 having a reduced taper portion 11 which is engaged by the screw 7 surmounted by a shoulder 12. The action of the screws is to 80 bear against the taper 11 and thus draw the shoulder 12 downwardly into tight engagement with the upper face of the collar 6. If desired the upper face of the collar 6 and under face of the shoulder 12 may be roughened, as indicated at 13, to tightly interlock 85 and prevent any relative twisting movement of the parts when tightened together by the screw or screws 7.

In Figure III, I have illustrated a different form of device in which I make use of the shank 8 with taper portion 11 and shoulder 12, surmounted, however, by the cap 14 recessed as at 15 to receive a grinding tool 16 which is locked in position in the recessed 90 cap member through the use of the set screw 17.

It will be understood that the foregoing described construction is adaptable for use with either spherical, toric or other forms of lens grinding tools. In order that my device may be most readily used with all of these different tools I preferably make a toric lens member separable from the base portion 1 but capable of ready application 105 thereto as desired. This result I accomplish by slotting the upstanding portion 6 or col-

lar on the base 1, as at the point 22, providing recesses to receive the pivot blocks 23 which are shaped to form a continuation of the collar extending from the socket 5 to the edge of the collar. These blocks have journaled therein the ends of the rods 25 which are secured in position as by the washers 24 fitting in grooves 26 countersunk into the blocks 23. The rods extend outward through the arms 27 of the yoke member 28 and terminate in the projecting threaded ends 29 receiving the lock nut 30 and washer 31 which secures in position the guide arms 4 locked between the washer 31 and the flange cap 32 at the outer end of each of the arms 27. In use the center stud is removed and the yoke 28 and associated parts slipped in position about the collar 6 with the blocks 23 engaged in the recesses 22. The stud 8 is then inserted in the socket 5 and clamped in position by the set screw when the flanged portion 12 thereof resting on the collar and on the upper portion of the blocks 23 will securely hold the toric device in position so that it may be employed with any kind of tool carried by the machine, while the member 9 may be provided with the pin 21 to lock the tool against rotation thereon.

On the other hand, when it is not desired to use the toric attachment, as for spherical grinding, the toric attachment is removed and the stud replaced. If preferred the tool holding stud member 9 may be provided with a flange cap 33 extending over and providing a closure for the recesses 22 to prevent access of abrasive or the like thereto. It is to be noted also that the yoke is preferably provided with an aperture 34 through which a wrench or screw-driver may be inserted to operate the locking screw 7. When the flange cap 33 is employed it is provided with the notches as at 35 which are just of sufficient size to receive the inner ends of the

arms 27 on the yoke 28 allowing of proper play of the yoke through oscillation of the guides 4 but overlapping the joint of the parts to exclude the abrasive and to especially protect the blocks 23 and their receiving slots, the cap portion of the flange extending down around the upstanding portion 6 of the body of the holder. When the toric attachment is removed the cap is preferably sufficiently rotated to bring the slots 35 out of alignment with the recesses at 22 so that the depending flange will entirely close up the recesses in this event.

I claim:

1. A device of the character described comprising a base portion having an upstanding collar, bearing blocks detachably associated with the collar, rocking guide arms carried by the bearing blocks, and a tool stud having a portion secured within the collar and a portion engaging the blocks for retaining the latter in position. 65

2. A device of the character described including a base portion having an upstanding slotted collar, bearing members secured in the slots of the collar, and guide arms mounted for rocking movement on the bearing members. 70

3. A device of the character described comprising a base portion having a socket, a toric arm yoke encircling the socket, bearings for the yoke detachably associated with the base member adjacent the socket, and a tool support detachably secured in the socket and engaging the bearing members for securing the latter in position. 75

In testimony whereof I have affixed my signature in presence of two witnesses.

ALBERT E. MAYNARD.

Witnesses:

ESTHER M. LAFLER,
ALICE G. HASKELL.
